UNITED STATES PATENT OFFICE.

TERENCE F. MCKENNA, OF LEOMINSTER, MASSACHUSETTS.

DESIGN FOR A PUFF-RETAINING COMB.

No. 39,501.

Specification for Design.

Patented Sept. 8, 1908.

Application filed July 17, 1908. Serial No. 444,149. Term of patent 14 years.

To all whom it may concern:

Be it known that I, TERENCE F. MCKENNA, a citizen of the United States, residing at Leominster, in the county of Worcester and State of Massachusetts, have invented a new, original, and ornamental Design for Puff-Retaining Combs; and I do hereby declare the following to be a full, clear, and exact specification of the same.

My invention relates to a design for puff retaining-combs—which is illustrated in the

accompanying drawings, in which the figure is an elevation of a puff retaining comb, showing my new design.

I claim:—

The ornamental design for a puff retaining comb, as shown.

TERENCE F. MCKENNA.
